(57) **CLAIM**

The ornamental design for a motor vehicle and/or toy replica thereof, as shown and described.

DESCRIPTION

FIG. 1 is a front left perspective view of a motor vehicle and/or toy replica showing my new design;

FIG. 2 is a rear left perspective view thereof;

FIG. 3 is a front right perspective view thereof;

FIG. 4 is a rear right perspective view thereof;

FIG. 5 is a left side view thereof;

FIG. 6 is a right side view thereof;

FIG. 7 is a front view thereof;

FIG. 8 is a rear view thereof; and,

FIG. 9 is a top view thereof.

The bottom view of the motor vehicle and/or toy replica forms no part of the claimed design.

The broken lines in FIGS. 1-6, 8, and 9 depict boundaries around de-emphasized elements, which illustrate environmental structure for the motor vehicle and/or toy replica and which form no part of the claimed design.
